UNITED STATES PATENT OFFICE

THEODORE H. MILLER, OF POUGHKEEPSIE, NEW YORK, ASSIGNOR TO THE DE LAVAL
SEPARATOR COMPANY, OF NEW YORK, N. Y., A CORPORATION OF NEW JERSEY

OIL-PURIFYING APPARATUS FOR MOTOR-PROPELLED VEHICLES

Application filed May 24, 1926. Serial No. 111,173.

The object of my invention is to provide a centrifugal liquid purifying or separating apparatus that is particularly adapted to be carried on moving motor-propelled vehicles and to be mounted thereon on a horizontal 5 axis. Such apparatus so mounted is known in the art and has been connected with the lubricating oil reservoirs or oil circulating systems of such vehicles.

The mounting of a centrifuge on a vertical axis has certain advantages, the chief of which is that any liquid contained thereon or any sediment deposited on its walls and which, during centrifugation, tends to equally distribute itself around the periphery, also tends, 10 when the bowl comes to rest, to settle therein without disturbing the balance of the bowl; that is, when the bowl is at rest, any liquid and sediment therein continues to be distributed approximately uniformly around the bowl axis, so that the bowl and its contents are approximately "balanced" when the centrifuge is again put into operation. With the centrifuge mounted on a horizontal axis, the contents tend to sink by gravity and settle at one side of (below) the bowl's axis. However, this disadvantage is often not serious, because, on restarting the bowl, any contained liquid, of course, equally distributes itself quickly around the periphery; and 15 I have found that, in horizontally mounted purifying bowls, the sediment collected on the bowl wall often displays little tendency to collect on that part of the bowl wall which, when the bowl is at rest, is at the bottom, but adheres for hours to that part of the bowl wall on which it is originally deposited. In other cases, however, the sediment, by gravity, becomes unequally distributed peripherally, and resists equal distribution for a 20 substantial time after the bowl is restarted. While this trouble can be overcome by mounting the bowl on a vertical axis, the disadvantage of so mounting a bowl on a moving vehicle is obvious, in that the shocks and strains imposed on the bearings are severe and tend to tilt or twist the bowl in its bearings, thereby preventing its smooth running and even its practical operativeness.

One object of the invention is to provide

for more certainly approximately balancing a bowl mounted on a horizontal axis in case of an unequal distribution of solid or semi-solid sediment on the bowl wall, although this feature of the invention is not indispensable 55 and it is not to be considered an implied element of the structure except where specifically claimed.

There are, however, other more serious factors that militate against the successful operation of a centrifuge on a locomotive or other moving vehicle even when the bowl is mounted on an axis extending horizontally and in the direction of movement of the vehicle. By reason of sudden stops, the bumping of the locomotive against cars, and other similar incidents, the bowl and its shaft are subjected to powerful forces that tend to throw or jerk them bodily in the direction of their axis. The spring bearings by which the shafts of centrifuges are customarily supported are incapable of absorbing the shocks 60 and strains set up by such forces. One of the principal objects of the invention is to provide a centrifugal purifying apparatus so supported and with such an arrangement of oil ports and passages as will adapt it to function with maximum efficiency and particularly to absorb the shocks incident to the use of any such apparatus on a locomotive 65 or other motor-propelled vehicle.

Another object of the invention is to so construct the purifying apparatus that the liquid being acted on will be always under liquid pressure and will never be allowed to escape as a spray.

A preferred embodiment of my invention, accomplishing the specified and other objects, is shown in longitudinal section in the accompanying drawing.

A purifier bowl *a*, preferably a single outlet bowl, is mounted on a hollow shaft having extensions *b* and *c*. Within the hollow shaft is an imperforate web *w* which divides the interior of the shaft into two axial passages *l* and *o*. The shaft extensions rotate in bearings *d* and *e*, which are flexibly supported in their pedestals by springs *s*. At each end of the shaft, backed by a cushioning spring *f*, is a thrust bearing plug *g* adapted to 90 95 100

bear against a stationary abutment *h* held in the bearing adjacent the end of the shaft.

A flexible tube *i*, which is connected with the lubricating oil reservoir or lubricating oil circulation system (not shown) of the engine, is in communication with an annular chamber *j* in the bearing *d* and, through port *h*, passage *l* and port *m*, all in the shaft extension *b*, with the interior of the bowl *a*. Port *n*, passage *o*, and port *p*, all in the shaft extension *c*, communicate with an annular chamber *q* in the bearing *e* and thence with a flexible tube *r*. Tubes *i* and *r* are connected, in any convenient way, with the oil supply for the engine and, together with the described connections between them, may conveniently be arranged either in the main oil circulating system of the engine or in a bypass therefrom.

The inlet passage *l* and outlet passage *o* communicate, through restricted passages in webs *t*, with the chambers at the respective ends of the shafts.

Around the bowl *a* is a metal belt *u*, which has a mass many times that of any irregular deposit of solids in the bowl.

The bowl may be geared to the driving shaft of the engine, but is preferably driven from a special motor (so that its speed will be constant regardless of the speed of the vehicle). The shaft is therefore provided with a pulley *v*, which may be belted to the motor shaft (not shown).

In operation, the bowl rotates at high speed. Dirty liquid (which will be contaminated lubricating oil if the apparatus is used for the purpose of purifying such oil) is fed, through the flexible inlet tube *i*, chamber *j*, port *h*, passage *l* and port *m*, into the bowl *a*, wherein centrifugal force throws the impurities heavier than the oil out against the shell while the cleaned oil is forced toward the center and out through the port *n*, passage *o*, port *p*, chamber *q* and tube *r*, which conducts it to the oil circulating system or the storage tank.

Enough oil to fill the chambers at the ends of the shaft passes through the restricted passages *t* to afford a liquid cushion adapted to damp any sudden movement of the bowl and shaft relative to the bearings.

The heavy belt *u* around the bowl is of such great mass that the effect of any irregularity of deposits of solids within the bowl will be so slight that the bowl can be stopped and, in spite of some settling of solids to the lower side, can be started and run again without excessive vibration.

The spring-backed bearing plugs *g* take the thrust when it is so long continued in one direction as to overcome the damping effect of the liquid in the chambers at the ends of the shaft.

The construction described is one which permits the liquid within the apparatus to be

maintained under a superatmospheric pressure and fill the liquid passages so that the liquid will not escape from the bowl as a spray.

While the invention is particularly intended for application to motor-propelled vehicles, it is capable of being applied to stationary engines.

Having now fully described my invention, what I claim and desire to protect by Letters Patent is:

1. The combination of a centrifugal purifying bowl with means to support it on a horizontal axis and to permit movement thereof in opposite directions parallel with the axis, and shock-absorbing means adapted to yieldingly resist such movements.

2. The combination of a centrifugal purifying bowl with means to support it on a horizontal axis and to permit movement thereof in opposite directions parallel with the axis, and shock-absorbing springs adapted to yieldingly resist such movements.

3. The combination of a centrifugal purifying bowl with means to support it on a horizontal axis and to permit movement thereof in opposite directions parallel with the axis, and movement damping means comprising chambers adapted to contain liquid to resist the end thrusts of the bowl, said chambers having restricted apertures permitting a throttled flow of liquid into and out of the chambers.

4. The combination of a centrifugal purifying bowl with means to support it on a horizontal axis and to permit movement thereof in opposite directions parallel with the axis, and shock-absorbing means adapted to yieldingly resist such movements, said shock-absorbing means comprising springs adapted to yieldingly resist such movements and chambers adapted to contain liquid also adapted to resist such movements, the chambers having restricted apertures permitting a throttled flow of liquid into and out of the chambers.

5. The combination with a horizontal slideable shaft, of a centrifugal purifying bowl mounted thereon, and means providing passages through which liquid is adapted to flow along the shaft to and from the bowl, of shock-absorbing means adapted to receive and damp end thrusts of the shaft.

6. The combination with a horizontal slideable shaft, of a centrifugal purifying bowl mounted thereon, and means providing passages through which liquid is adapted to flow along the shaft to and from the bowl, of shock-absorbing springs adapted to receive and damp end thrusts of the shaft.

7. The combination with a horizontal slideable shaft, of a centrifugal purifying bowl mounted thereon, and means providing passages through which liquid is adapted to flow along the shaft to and from the bowl, and

means providing a chamber communicating with said liquid flow passages and affording a shock-absorbing device adapted to receive and damp end thrusts of the shaft.

8. The combination with a hollow slideable shaft and a centrifugal purifying bowl mounted thereon, of means to allow liquid to flow into and out of the shaft and into and out of the bowl, and means at each end of the shaft forming an end chamber one wall of which is movable with the shaft and relatively to the other wall, said chambers having restricted openings communicating with the hollow shaft and through which liquid is adapted to flow.

9. The combination with a centrifugal purifying bowl provided with an inflow port and an inflow passage leading therefrom to the separating space of the bowl and with an outflow port communicating with the interior of the bowl adjacent its inner wall, of a horizontal shaft on which the bowl is mounted, and spring bearings in which opposite ends of the shaft turn, the shaft being provided with liquid inflow and outflow passages communicating with the said ports respectively.

10. The combination with a centrifugal purifying bowl, of a shaft on which the bowl is mounted, and bearings at opposite ends of the bowl in which the shaft rotates, the shaft having inlet and outlet passages for liquid communicating with the bowl and the bearings having annular chambers, respectively to receive and discharge liquid, communicating with the respective passages in the shaft.

11. The combination with a centrifugal purifying bowl, of a hollow shaft providing an axial liquid flow passage and on which the bowl is mounted, and bearings in which the shaft turns, the bearings having annular chambers and the shaft having ports affording communication between said chambers and the axial liquid flow passages in the shaft.

12. The combination with a centrifugal purifying bowl and a shaft on which the bowl is mounted on a horizontal axis, of shaft bearings permitting movement of the bowl and shaft in opposite directions parallel with their axis, and movement damping means at the ends of the shaft comprising chambers adapted to contain liquid and having liquid outlets and inlets of cross section small relatively to that of the shaft.

13. The combination with a centrifugal bowl and a shaft on which the bowl is mounted, of radially yieldable bearings in which the opposite ends of the shaft are both rotatable and axially slideable, the shaft having liquid inflow and outflow passages communicating with the bowl.

14. The combination with a centrifugal bowl and a shaft on which the bowl is mount-

ed, of bearings in which the opposite ends of the shaft are both rotatable and axially slideable, the shaft having liquid inflow and outflow passages communicating with the bowl, of thrust bearing plugs at the ends of the shaft and relatively to which the shaft is slideable and webs carried by the shaft, the space between the web and plug enclosed by the shaft at each end thereof forming a liquid-containing chamber, said chamber having a restricted orifice for inflow and outflow of liquid.

15. The combination with a centrifugal bowl and a hollow bowl-supporting shaft divided into a plurality of liquid flow passages, of bearings in which the opposite ends of the shaft are rotatable and axially slideable, there being a port adapted to admit liquid to one of said flow passages, a port adapted to convey liquid from the last named flow passage to the bowl, a port adapted to convey liquid from the bowl to another of said passages and a port adapted to discharge liquid from the last named passage, and webs carried by the shaft and constituting the end of walls of said passages, there being chambers beyond the webs and restricted liquid flow passages through the webs.

16. A centrifugal bowl and a concentric mass encircling the periphery of the bowl and of a weight exceeding the weight of a volume of water adapted to fill the bowl.

In testimony of which invention, I have hereunto set my hand, at Poughkeepsie, New York, on this 15th day of May, 1926.
